UNITED STATES PATENT OFFICE.

CHARLES E. PRATT, OF CHICAGO, ILLINOIS, ASSIGNOR OF ONE HALF TO
HUGH CUNNINGHAM, OF SAME PLACE.

FARE-REGISTER.

SPECIFICATION forming part of Letters Patent No. 319,847, dated June 9, 1885.

Application filed April 9, 1884. (No model.)

To all whom it may concern:

Be it known that I, CHARLES E. PRATT, of Chicago, county of Cook, and State of Illinois, have invented certain new and useful Improvements in a Fare-Register, of which the following is a full, clear, and exact description, that will enable others skilled in the art to which it appertains to make and use the same, reference being had to the accompanying drawings, forming a part of this specification.

This invention relates to improvements in that class of registers or devices used by conductors on street-railway lines for keeping a register of the fares collected and the number of trips made; and it consists of certain novel features of construction and combinations of parts, as will be hereinafter more fully set forth and claimed.

Figure 1 is an exterior front view of the register in perspective. Fig. 2 is a view of the interior, the inclosing face-cap and parts of the registering mechanism being removed. Fig. 3 is a similar view, with the registering-dials in proper position, which are not shown in Fig. 2; Fig. 4, a plan view of the interior of the inclosing face-cap. Fig. 5 is a view of the interior mechanism, the registering-dials and the ring immediately back of the same being removed so as to expose the parts underneath. Fig. 6 is a side elevation; Fig. 7, a view of the opposite side; and Figs. 8, 9, 10, 11, 12, 13, 14, 15, 16, 17, 18, 19, 20, and 21 are detached details of construction of different parts of the device.

Referring to the drawings, A represents the removable inclosing face-cap, which may be locked or otherwise secured in place so that the cap cannot be removed by the conductor using the same for the purpose of tampering with the operating mechanism.

A' is the back of the inclosing-case; A², a foundation-plate rigidly secured to the inside of the inclosing-back, to which the different parts of the mechanism are attached.

The operating-handle or prime mover A³ projects through the lower end of the inclosing cap or case, the opposite or inner end being attached to the post a projecting from the front of the angular lever-arm A⁴. This lever-arm extends across the case, as shown in Fig. 2, one end being loose, so as to follow the move-

ment of the operating-handle, while the opposite end or point of junction with the angle extension a' is secured upon the post a² and adapted to have a pivotal action in relation to the same. Figs. 1, 2, and 3 show the normal position of the operating-handle and the lever-arm A⁴. Fig. 5 illustrates the opposite position. When these parts are returning to a normal position, the edge of the lever-arm 60 comes in contact with the stop-post a³, preventing a back movement beyond that point.

The spring A⁵ is coiled around the post A⁶, one projecting end having a tension bearing against the inner side of the post a⁴, the opposite end having contact with the angle-extension a' of the lever-arm A⁴, as shown in Figs. 2 and 5 of the drawings, by which means the operating-handle and the lever-arm are automatically returned to a normal position. By 70 this construction and arrangement the lever-arm has an action or movement similar to a bell-crank.

The body of the spring B is rigidly secured to the collar b, mounted on and adapted to have 75 a slight rotary movement on the post a³, and has the two spring-arms a⁵ a⁶ projecting from opposite sides of the post and running back of or behind the lever-arm A⁴. The bell-hammer a⁷ is mounted on the end a⁵, the companion end, a⁶, 80 being somewhat longer, as shown in Fig. 2. A flat spring, a⁸, is riveted at one end to the lever-arm, the opposite end being loose, and having a tripping-pin, b', fastened thereto, which passes below and rests in a notch cut in the lower 85 edge of the lever-arm, as shown in Figs. 2 and 15. The pin b' is adapted to have a tripping and frictional contact with the arm a⁶ of the spring B on both the forward and back movement. When the operating-handle is pulled 90 down or outward, the upper side of this tripping-pin comes in contact with the extreme end of the spring-arm a⁶, moving it along with it, and causing the companion arm carrying the bell-hammer to move in the same direction by a slight rotation of the collar b on the post a³; and just as the operating-handle and the lever-arm connected therewith reach the limit of their movement from a normal position the arm a⁶ becomes too short to retain contact with the tripping-pin, which slips by the end, when the spring b², having one end in con-

tact with the arm a^6 , throws the spring B back, causing the hammer to strike the bell or gong B' . The spring b^2 is coiled around the pivot-post a^2 back of the lever-arm, one end resting 5 against the post a^4 , and the opposite end bearing against the arm a^6 for the purpose above described, as shown in Figs. 2 and 5. The arm a^6 is prevented from striking the bell-hammer when it flies back by the stop b^3 .

10 (Shown in Fig. 2.) After the bell has sounded and the hand of the operator is released from the operating-handle, the mechanism in returning to a normal position brings the back of the tripping-pin in contact with the end of 15 the spring-arm a^6 , which preceded it to a normal position. The tripping-pin, being rounded or beveled on the back side, rises up and slips over the arm a^6 , the flat spring a^8 throwing the pin down again in proper position to 20 actuate the striking-hammer when another stroke is required.

The stationary rack-bar B^2 (shown in Figs. 5, 7, and 11) is attached by flange b^{12} to plate A^2 at one side of the operating-lever. The upper end of the spring locking-pawl B^3 is secured to the front side and loose end of the lever-arm in order to have a slight pivotal action, the opposite end being adapted to engage with the toothed ratchet-bar B^2 and lock the mechanism against a back movement before a full stroke of the operating-handle is completed. The locking-pawl B^3 is made somewhat wider toward the upper end, as shown in Fig. 19, in order to have a wedge-like contact with the inner projecting edge of the post B^4 on plate A^2 , and cause a lateral inward movement of the pawl for the purpose of throwing the same out of engagement with the ratchet-bar just at the moment the operating-handle is pulled out 40 to its extreme limit. When thrown out of engagement by post B^4 , the hook end of the locking-pawl drops back a little and bears against the inner side of the ratchet-bar while returning to a normal position, and when the pawl passes 45 above the ratchet it is released from its side contact with the ratchet-bar and is thrown into line again with the said ratchet-bar by the split-spring end b^{14} attached to the lever-arm. This arrangement prevents the bell from being 50 sounded until the operating-handle has been drawn out to its extreme limit and the fare registered.

The round post B^5 is centrally located and is rigidly secured to the plate A^2 . This post 55 supports the mechanism necessary to actuate the registering-dials B^6 B' , shown in Figs. 1, 3, and 8.

The rotating sleeve C incloses the post B^5 and carries, near its back end, the toothed 60 ratchet-wheel C' , and on the front end the unit-dial B^6 .

A small angle-bracket, a^9 , (shown in Figs. 8, 9, and 10,) is rigidly secured to the front side of the lower ratchet-wheel, C' . The inwardly projecting and raised end of this bracket 65 is perforated for the free movement of the loose locking-pin b^4 , which is adapted to have

an endwise movement through a hole, b^3 , (see Fig. 8,) in the ratchet-wheel C' . The flat spring b^5 on wheel C' is perforated at the loose 70 or yielding end for the passage of the pin, the other end being riveted to the ratchet-wheel, the pin being adjustably retained in relation to said ratchet-wheel and spring by means of the collar b^6 , Fig. 8, formed on the pin. The lower end of this pin projecting below the ratchet-wheel is adapted once in each revolution to have contact with the rising step b^7 on plate A^2 , and which has the effect of forcing the pin 75 up into engagement with one of the holes b^8 in the perforated companion ratchet-wheel C^2 and moves the same forward one notch, the flat spring b^5 returning the pin to its normal position the moment it leaves the step b^7 . The ratchet-wheel C^2 is secured to the lower part 80 of the exterior rotating sleeve, C^3 , mounting the larger indicating-dial B' near the front end. This larger dial, as shown in Fig. 8, has an annular recess or depression into which the smaller or companion dial fits for the purpose of bringing the indicating-surfaces of the 85 dials to the same level.

The unit-dial B^6 is provided with numerals running from 0 to 9 and moves one notch or 90 number with each sound of the bell, the companion-dial having numerals running from 1 to 9, leaving a blank space between the 1 and 9, so that when 0 character on the unit-dial is opposite this blank the dials are at zero.

The sleeves C^3 , carrying the companion 95 ratchet-wheels C' C^2 , are prevented from having an endwise movement by means of the angle-plate b^9 , having the projecting part fastened to the base-plate A^2 , and the opposite end perforated to pass over the sleeves and post B^5 , and 100 bent over at right angles close to the upper ratchet-wheel, as shown in Figs. 2, 5, and 6. The upper ends of these sleeves have square shoulders, the perforations in the dials being 105 of a corresponding shape and retained in proper relation to said sleeves by the square washers c c' , shown in Figs. 8, 17, and 18, and c' in Fig. 3.

Rigidly secured at one end to the angle plate 110 b^9 are spring clicks c^2 and c^3 , having their opposite or loose ends curved outward, so as to 115 present a rounded bearing-surface to the depressions between the teeth of the companion ratchet-wheels C' and C^2 and prevent the same from moving in either direction unless actuated 120 by the proper mechanism.

One end of the feed-dog C^4 , Figs. 2 and 5, is pivoted to the rear side of the lever-arm A^4 , while the opposite or loose end is adapted to move the same forward one tooth at a time 125 with each pull of the operating-handle. This operation imparts a corresponding movement to the smaller or upper dial, B^6 , carrying the indicating-characters on its face. When the under ratchet-wheel has been fed around to the tenth tooth, the pin b^4 is thrown into engagement with the upper ratchet-wheel, C^2 , moving it one tooth or number and thus bringing 130

ing the second dial B' forward one figure, the two dials now indicating 10, as shown in Fig. 1. The upper ratchet-wheel and the dial B' carrying the outer circle of figures now remain stationary until the under ratchet-wheel and the smaller dial complete another revolution, when the upper perforated wheel is moved another notch, the dials now indicating 20, and so on continuously until the highest number is reached that the numerals on the two dials are capable of indicating—namely, 99—when the same may be turned back to zero by means of the following mechanism:

The ratchet-wheel C^5 (shown in Fig. 4) is adapted to engage loosely with and rotate on the top of the post B^5 and lies closely against the inside of the inclosing cap. One end of the shifting-hand C^6 is rigidly secured to the hub c^9 of wheel C^5 outside and in front of the ratchet-wheel, while the opposite end, when in a normal or stationary position, engages with the curved end of the locking-arm C^7 , this position of the hand being indicated by the dotted lines in Figs. 2 and 3. The front end of the hub c^9 of the ratchet-wheel has an interior screw-thread, and projects through to the outside of the inclosing cap, where a screw-plug, c^4 , having an enlarged milled head, C^4 , screws into the hub c^9 of the ratchet wheel, as shown in Fig. 1, for the purpose of turning the hand C^6 around from the outside. The locking-pawl c^5 engages with the ratchet-wheel C^5 , and is retained in relation to the same by its spring c^6 . This prevents the ratchet-wheel from turning in but one direction, and that is to the right, as shown by arrow in Fig. 4, which is opposite to the direction in which the dials are moved by the feed mechanism.

The bracket D is pivoted to the back of the case, as shown in Figs. 2, 3, 5, and 11, and has the locking-arm C^7 attached thereto. The edge d of this bracket is curved inward a little, so as to catch and prevent the end of the lever-arm A^4 from passing, as shown in Figs. 2, 6, 7, 11, and 19, should an attempt be made to operate the registering mechanism when the hand C^6 is not in engagement with the hook end c^7 of the arm C^7 . If the hand C^6 is engaged with the arm C^7 , the bracket is forced back out of the way and the lever-arm will pass by without coming in contact with the same. This bracket is adapted to have a slight swinging movement on its pivot d^0 , and when it is desired to release the hand C^6 from engagement with the arm C^7 it may be done by pulling on the rod d^1 connected with the bracket D and projecting out through the side of the case. When the operator lets go of the rod, the bracket is drawn inward by means of the spiral spring d^2 . (Shown in Fig. 5.) The hand C^6 , being disengaged from the locking-arm, may be made to move around over the face of the dials, and, by coming in contact with the posts d^3 d^4 projecting from the faces of the same, moves the dials back to zero.

D' , Fig. 3, represents a ring (shown partly

broken away in Fig. 2) secured by screws or otherwise to the front end of posts A^6 and B^4 , and at a point just back of the larger dial. 70

On the side adjacent to the bracket D this ring is provided with the rising step d^5 , Figs. 2, 3, and 11, which gradually rises from a level until the highest point is reached just opposite the end of the arm C^7 , where it terminates. This raised step serves the purpose of raising up the outer end of the hand C^6 from contact with the posts d^3 d^4 when the dials are turned to indicate zero, and carry it along into engagement with the hook end of the arm C^7 . These two dials may be reset or turned back to zero at any time, as they are not intended to give a permanent or total representation, but ordinarily they are reset each half-trip. 85

The toothed trip-wheel D^2 has a rotating bearing on the bell-post d^6 , as shown in Figs. 2, 3, 5, 6, and 7. One end of an angular bracket, D^3 , is also connected with the post d^6 , and extends outward and upward and supports the pinion d^7 in engagement with the toothed trip-wheel D^2 . The teeth of this wheel are numbered in regular order, its function being to keep a register of the trips, always showing just how often the dials have been set back to zero. The hand C^6 , when moved in the direction of the arrow for the purpose aforementioned, strikes the pinion d^7 and turns it one notch as it passes by; the pinion in turn transmits the motion to the wheel D^2 100 and registers the passage of the hand C^6 . The click d^8 locks the pinion in the position to which it is moved.

The total or permanent registering mechanism consists of a series of adding disk-wheels, D^4 , D^5 , D^6 , D^7 , mounted on the stationary shaft E , having square ends and supported by the lugs e e' . Each of these disks have numerals on their peripheries running from 0 to 9. The first or units disk, D^4 , registers one every time that the operating-handle is pulled out, and the second disk will move one notch to every revolution of the units-disk, the third disk moving in its order, and so on in this manner registering from one 110 up into the thousands. Each one of these numbering-disks is provided with companion toothed wheels, e^2 e^3 e^4 e^5 , formed on the same hub, as shown in Fig. 16. The toothed ratchet-wheel e^2 , loose upon shaft E and on the outside of the units-disk, and connected therewith, as hereinafter described, is actuated by the push-finger E' engaging with the same, the opposite end of which push-finger is attached to the lever-arm A^4 and moves simultaneously therewith. The pawl h^3 engages with the under side of the wheel e^2 and locks the same against a back movement. The pin F passes through openings in the wheel e^2 and the companion disk-wheel D^4 , and has a longitudinal movement on the stationary shaft for the purpose of engaging with the next succeeding toothed wheel e^3 once in each revolution of the unit-wheel D^4 , which gives one- 120 125 130

tenth of a revolution to the wheel D^5 , registering tens, by means hereinafter described. Fig. 20 is a detached view of this pin, and Figs. 12, 13, 14, and 16 are views of this part of the mechanism.

The flat-spring f , Fig. 14, is secured at one end to the unit-disk, near the periphery, the opposite end extending over near the center and being perforated for the passage of the pin F , which is provided with the collar f' , which is placed between the loose end of the spring and the face of the disk-wheel, by which means the pin F is retained in an adjustable position. The endwise movement of this pin, in order to bring the same into engagement with the toothed wheel e^3 , is effected by means of the outer end of the pin coming in contact once in each revolution with the beveled post F' , attached to the shaft E , Figs. 2, 3, 5, 12, and 13, which latter two show the pin in two different positions. The spring f returns the pin to its normal position when it ceases to have contact with the post F' .

$F^2 F^3$ are corresponding pins for transmitting motion to the series of numbering-disks in regular order, the pins being of the same form and having precisely the same action as that of the pin F , already described.

The beveled posts F^4 and F^5 , attached to plate A^2 , throw the pins $F^2 F^3$ into engagement with the toothed wheels $e^4 e^5$ between the disks once in each revolution in their different order.

$h h' h^2$ are spring-clicks respectively engaging with the toothed wheels e^3 , e^4 , and e^5 for the purpose of locking the same as they are moved around tooth by tooth.

Openings in the case, as shown in Fig. 1, permit the characters on the different registering mechanism to be seen without removing the cap. However, the permanent register $D^4 D^5 D^6 D^7$ and the trip-wheel D^2 may be invisible, a view of the dials $B^6 B^7$ being ordinarily sufficient.

Having thus described my invention, what I claim as new, and desire to secure by Letters Patent, is—

1. In a fare-register, the combination of a plate having a ratchet-bar and post, B^4 , a lever-arm, an operating-handle attached to one end of said lever-arm, and a locking-pawl pivoted to the lever-arm and extending downwardly in front of the ratchet-bar and having its upper end wider than its lower end, substantially as described.

2. In a fare-register, the combination, with

a lever-arm having an operating-handle and a feed-dog, of a unit-dial, B^6 , having loose sleeve C , mounted on a shaft and provided with a ratchet-wheel, C' , having adjustable pin b^4 , a dial, B^7 , having loose sleeve C^3 , inclosing sleeve C and provided with perforations b^8 , and a step, b^9 , for operating the pin b^4 , substantially as described.

3. In a fare-register, the combination, with the indicating-dials B^6 and B^7 , respectively having posts d^4 and d^5 , of a ratchet-wheel having shifting-hand C^6 , means for locking it against a back movement, and a plug or cap, C' , for turning it, substantially as set forth.

4. In a fare-register, the combination, with the indicating-dials B^6 and B^7 , having, respectively, posts d^4 and d^5 , of a shifting-hand, C^6 , an arm C' , and a rising step, d^9 , for raising said shifting-arm above the posts, substantially as described.

5. In a fare-register, the combination, with the hand C^6 of the arm C' , provided with the hook end c' , the bracket D , and rod d' , whereby said arm may be drawn back so as to release said hand from engagement with the hook end c' , substantially as and for the purpose described.

6. In a fare-register, the combination of a lever-arm, A^4 , the bracket D , having the locking-arm C' , inwardly-curved edge d , and spring d' , and the hand C^6 , substantially as described.

7. In a fare-register, the combination of a registering-dial having a post upon its face, a toothed trip-wheel, D^2 , a pinion, d^7 , interposed between said dial and wheel and meshing or gearing with said wheel, and a hand, C^6 , pivoted in front of the dial and of sufficient length to strike the lowermost cog of pinion d^7 , substantially as described.

8. In a fare-register, the combination of the lever-bar having a push-finger, a ratchet-wheel, C^2 , mounted on the shaft E , the unit-wheel D^4 , the pin F , having collar f' and spring f , a toothed wheel, e^3 , and the beveled post F' , substantially as described, whereby said pin is forced endwise into engagement with said wheel e^3 and rotates the same one notch in each revolution of the unit-disk, and is automatically returned to its normal position when released from contact with said post.
